UNITED STATES PATENT OFFICE.

THEODORE J. NELSON, OF CHICAGO, ILLINOIS, ASSIGNOR TO COLONIAL LAMP & FIXTURE WORKS, OF CHICAGO, ILLINOIS, A CORPORATION OF ILLINOIS.

LIGHTING FIXTURE.

Application filed March 14, 1921, Serial No. 452,276. Renewed May 20, 1925.

To all whom it may concern:

Be it known that I, THEODORE J. NELSON, a subject of the King of Sweden, residing at Chicago, in the county of Cook and State 5 of Illinois, have invented certain new and useful Improvements in Lighting Fixtures, of which the following is a specification.

My invention has reference more particularly to a portable lighting fixture similar to that shown in my copending application Serial No. 389,294, which has a flexible hanger with a counterweight, whereby the fixture may be mounted by merely engaging the flexible hanger over an object.

An important feature of my present invention is the use of a hanger comprising two parts which connect the fixture and counterweight, and are not only capable of supporting the fixture in all places where 10 a strap or band hanger may be used, but may be spread apart to satisfactorily engage over objects having irregularities or projections in the upper face which would render the use of a strap support undesirable. Moreover, the separating of the two parts 15 may be utilized to increase the stability of the suspended fixture, and the two parts may be independently adjusted on the supporting object to level up the fixture, particularly if one part engages over a higher portion of the object than the other.

The principal objects of my invention are to provide an improved portable fixture; to connect a counterweight to the fixture by 20 means of a plurality of flexible members, such as cords, so that the fixture may be suspended by merely engaging the members over a support; to permit the said members to be spread apart to straddle or avoid irregularities in the upper surface of the support over which the fixture is suspended, and also to increase the stability of the fixture 25 when suspended; to permit separate adjustment of said members for the purpose of leveling up the fixture; to provide an improved construction of the fixture whereby it is particularly adapted to be suspended; to afford an improved connection of the flexible hanger with the fixture; to provide an improved counterweight; and, in 30 general, to provide an improved fixture comprising flexible supporting members which increase the utility of the fixture and

render it more desirable because of its wide range of usefulness.

On the drawings—

Fig. 1 is a perspective view of my improved fixture suspended over the head of a bed;

Fig. 2 an enlarged view of the fixture 60 with parts broken away and in section to disclose details of construction;

Fig. 3 is a sectional view on the line 3—3 of Fig. 2;

Fig. 4 a sectional view of the counterweight on the line 4—4 of Fig. 2; and

Fig. 5 is a view similar to Fig. 3 showing a modification of the invention;

Referring to the drawings, the reference numeral 1 indicates as a whole the fixture 70 base, which comprises a flat shell 2 having a tubular goose neck 3 extending forwardly and upwardly from the front face thereof, and carrying a socket 4 at the outer end in which an electric lamp 5 is mounted. The 75 shell 2 has a pair of laterally spaced openings 11 in the front wall thereof and at a short distance from the top, through which the corresponding ends of a pair of flexible supports 12, preferably in the form of 80 cords, are inserted into the interior of the shell, the other ends of these supports, or cords, being connected at laterally spaced points to a weight 14. This weight is sufficient to counterbalance the fixture, when 85 the cords are engaged over a support, and because of the spaced connection of the cords with the shell 2 and weight 4, said cords tend to normally maintain a spaced 90 relation.

A plate 6 is inserted and secured in the rear of the shell 2 and is of suitable weight so that when the fixture is suspended by the cords 12 it counterbalances the goose neck 3, socket 4, and other parts of the fixture 95 05 at the front of the shell 2, so that the shell 2 is maintained in an upright position as shown in Fig. 2, this result being also facilitated by the direction in which the cords 12 emerge from the shell 2, which forms a bend 100 in the cords which serves to some extent to maintain the upright position of the fixture.

The plate 6 may be secured to the shell 2 in any convenient manner, being preferably seated within the marginal flange of 105 the shell against a stud 7, and having a screw

8 inserted therethrough into the stud. This screw is countersunk in the plate, and a felt back 10 fastened on the rear surface of the plate 6 so that the fixture will not scratch 5 or mar any surface with which it comes in contact.

A chamber 9 is left between the shell 2 and plate 6 into which the ends of the cords 12 extend, and these are tied together in 10 the chamber in a knot 13, or otherwise fastened so that they will not pull out of the 15 openings 11.

The counterweight 14 consists of a heavy back plate 15 having a face plate 16 secured 15 thereto by one or more screws 17 so as to clamp the ends of the cords 12 therebetween and hold same in the desired spaced relation.

In the preferred construction each cord 12 contains a single conductor 18, which at 20 one end extends into the chamber 9 of the fixture, and is connected through the goose neck 3 with the socket 4, and at the other end these conductors extend with the cords in between the plates 15 and 16, and are 25 connected to the corresponding wires of a lamp cord, or twin conductor, 19, which latter extends out from the counterweight 14 to a suitable distance, and has an attachment plug 20 at the end. To properly admit the lamp cord 19 to the space between 30 the plates 15 and 16 the former plate preferably has a flange 21 at its lower end with an aperture having an insulated bushing 22 therein through which the lamp cord 19 is passed.

In the modified construction shown in Fig. 5 the lamp cord which is indicated at 23 leads into the lower end of the fixture base 2 through an insulated bushing 24, and thence through the goose neck 3 to a socket 40 on the outer end of the neck or arm 3 in the same manner as in the previously described construction. The suspending cords 25 in this modified form of construction do 45 not therefore contain the wires or conductors such as shown at 18 in the preferred construction but are merely flexible members of any suitable type.

The fixture may have any suitable shade 50 mounted thereon, a convenient type being illustrated in Figs. 1 and 2, and shown to comprise a circular band 26 which engages on the upper end of the socket 4, and is held in place by the lamp when the latter is 55 screwed into the socket 4, this band being provided with a laterally extending arm 27 having a pair of toggle links 28 and 29 pivoted to the outer end thereof, with a lamp shade 30 pivoted to the outer end of 60 the link 29. The band 26 is rotatable around the end of the socket 4 for adjusting the shade, and by adjusting the toggle links 28 and 29 angularly and adjusting the pivotal connection thereof with the arm 27 and shade 30 the latter may be turned down 65

alongside of the lamp 5, and thereby adjusted to any position in which the shade may be desired.

It will be observed by referring to Fig. 1 that the provision of the fixture with two 70 supporting cords 12 renders it possible to spread the cords apart to avoid any irregularities or ornamentation on the upper surface of the support over which the cords 12 are engaged, as for example the raised 75 part 31 on the head of the bed, and the cords may also be separated in any case to stabilize or prevent swinging of the fixture about a vertical axis. Furthermore, if the portion of the object over which one 80 of the cords is hung is somewhat higher than the portion of the object over which the other cord is hung, either cord may be adjusted to level up the fixture, such adjustment merely resulting in a tipping of the 85 weight 14 to some extent.

While I have shown and described my invention in a preferred form I am aware that various changes and modifications may be made without departing from the principles 90 of my invention, the scope of which is to be determined by the appended claims.

I claim as my invention:

1. The combination of a lighting fixture comprising a plate having a lamp mounted thereon at one side, and a pair of flexible supporting members having the plate connected therewith so that the latter is maintained by gravity in an upright position when supported by said members, said members being spaced apart so as to hold the plate against twisting movement around the vertical axis when suspended by said members.

2. The combination of a lighting fixture, comprising a base having a pair of spaced flexible supporting members connected thereto so as to be maintained by gravity in an upright position when supported by said members, a lamp holder mounted on one side of the base and a substantially flat face on the other side of the base adapted to engage an upright surface for holding the fixture against turning movement when suspended by the flexible members.

3. The combination of a lighting fixture comprising a flat base having a lamp holder at one side thereof, a pair of spaced flexible supporting members connected to the base so that the latter is maintained by gravity 120 in an upright position when supported by said members, and electrical conductors extending through the flexible members into the base.

4. The combination of a lighting fixture comprising a substantially flat base having a lamp holder mounted thereon at one side of the base, a pair of spaced flexible supporting members connected to the base for suspending the latter in an upright position,

- and a counterweight connected to the flexible supporting members at a distance from the base for holding the latter in equilibrium when intermediate portions of the flexible members are loosely engaged over a support. 5
5. The combination of a lighting fixture comprising a substantially flat base having a lamp socket at one side thereof, a pair of spaced flexible supporting members connected to the base so as to support the latter in an upright position, a counterweight connected to the flexible members at a distance from the base so as to hold the latter in equilibrium when intermediate portions of the flexible members are loosely engaged over a support, and electrical conductors leading into the base and connected to the lamp socket. 10
6. The combination of a fixture comprising an upright base having a socket carried thereby at a distance in front of the base, a pair of laterally spaced flexible supporting members connected to the front of the base near the top, a weight at the back of the base for counterbalancing the lamp socket and attached parts when the fixture is suspended by the flexible supporting members, and a weight connected to the flexible supporting members at a distance from the fixture so as 25 to hold the latter in equilibrium when intermediate portions of the flexible supporting members are engaged over a support.
7. The combination of a lighting fixture having a pair of flexible supporting members connected thereto at laterally spaced points, a weight connected to the flexible supporting members at a distance from the fixture so as to hold the latter in equilibrium when intermediate portions of the flexible members are engaged over a support, said members being loose from the support so that they may be shifted lengthwise to change the elevation of the fixture and may be shifted laterally along the support for 30 horizontally adjusting the fixture.
8. In a device of the class described, the combination of a lamp holder having a pair of flexible supports connected thereto at laterally spaced points, a lamp socket on the holder at one side of the plane of said flexible supports, a counterweight on the holder at the other side of said plane, and a weight on the flexible supporting members at a distance from the lamp holder for holding the lamp holder in equilibrium when intermediate portions of the flexible members are engaged over a support. 50
9. In a device of the class described, the combination of a flat base having a socket thereon at a distance from the front of the base, a pair of flexible supporting members leading out from the front of the base near the top thereof at laterally spaced points so as to hold the base in an upright position when suspended by said supporting mem- 55 bers, and a weight connected to the flexible members at a distance from the base and adapted to counterbalance the latter, when intermediate portions of the flexible members are loosely engaged over a support. 70
10. In a device of the class described, the combination of a lamp holder comprising an upright base, a lamp socket carried by the base and spaced from the front thereof, a pair of laterally spaced cords extending out at the front of the base, and having a counterweight connected to the opposite ends thereof, electrical conductors in the cords leading from the counterweight through the base to the socket, and a weight secured to the base at the rear so as to hold the latter in upright position when suspended by the flexible supporting members. 75
11. In a device of the class described, the combination of a flat shell having an arm extending forwardly therefrom and provided with a lamp socket at the outer end, a pair of spaced apertures in the front wall of the shell near the top thereof, a flexible supporting member extending outwardly through each aperture, a weight connected to the flexible supporting members at a distance from the shell, and a plate detachably secured to the back of the shell and adapted to counterbalance the forwardly extending arm and socket and attachments thereon, and hold the shell in an upright position when the latter is suspended by the flexible supporting members. 80
12. In a device of the class described, the combination of a fixture comprising a flat shell having an arm extending forwardly therefrom adjacent the lower end and provided with a socket on the outer end thereof, a pair of laterally spaced apertures in the front wall of the shell near the top thereof, a flexible supporting member extending outwardly from the shell through each aperture, a weight connected to the flexible supporting members at a distance from the shell 90 and adapted to hold the latter in equilibrium when intermediate portions of the flexible members are loosely engaged over a support, electrical conductors leading from the socket to the interior of the shell, and therefrom 95 through the flexible supporting members to the weight and having extensions leading from the weight and provided with an attachment plug at the outer ends thereof, and a plate secured to the rear of the aforesaid shell and spaced from the front wall to provide a compartment for the electrical conductors and the ends of the flexible supporting members, said plate being adapted 100 to counterbalance the portions of the fixture 105 at the opposite side of the flexible supporting members so as to hold the shell in an upright position when suspended by the flexible members. 110
13. In a device of the class described, the 115
- 120
- 125
- 130

combination of a substantially flat base having a lamp holder at one side thereof, a pair of spaced flexible supporting members for suspending the latter in an upright position, 5 said members being connected to the base so that the portion of the latter at one side of the members substantially balances the lamp holder and the portion of the base at the other side thereof, and a counterweight connected 10 to the flexible members at a distance from the base so as to counterbalance the base when intermediate portions of the members are loosely connected over a support.

14. In a device of the class described, the combination of a hollow base having a socket 15 at one side thereof, a pair of spaced flexible supporting members connected to the base for holding the latter in an upright position, a counterweight on said members at a distance from the base for holding the latter 20 in equilibrium when intermediate portions of the members are loosely engaged over a support, and electrical conductors leading into the interior of the base and connected to the socket.

THEODORE J. NELSON.
